UNITED STATES PATENT OFFICE.

RICHARD KARL SCHMID AND WALTER PAUL WEZEL, OF STUTTGART, GERMANY.

APPARATUS FOR PRODUCING PULSATING AIR PRESSURE.

Application filed June 25, 1924. Serial No. 722,404.

To all whom it may concern:

Be it known that we, RICHARD KARL SCHMID, a citizen of the Republic of Germany, and a resident of Stuttgart, Germany, 5 and WALTER PAUL WEZEL, a citizen of the Republic of Germany, and a resident of Stuttgart, Germany, have invented certain new and useful Improvements in Apparatus for Producing Pulsating Air Pressure, of 10 which the following is a specification.

Alternating or pulsating air pressure producers are known in which the admission and discharge of air are controlled by slots, and alternating or pulsating air pressure 15 producers are also known, in which the pressure and suction air are controlled by one valve.

The present invention is characterized in that the valve is utilized only for controlling the discharge of air, whilst the air drawn in, is admitted through inlet slots in the compressor cylinder.

This arrangement has the advantage that a considerably larger cross-section is available for the suction than for the discharge, since practically the whole circumference of the cylinder is available for the suction port.

This difference in capacity of the two devices for the admission and discharge is 20 necessary, as the suction takes place with a very imperfect vacuum of, say, about 0.5 atmosphere, whilst during the discharge, the air is compressed to about 1.2 to 1.5 atm.

In the latter case the valve may therefore 25 be considerably smaller. This is a great advantage, since the clearance caused by the connection pipe to the valve becomes considerably smaller.

On the other hand, another and decisive 40 advantage of the valve construction for the air discharge is that it is possible at any moment to fix the timing of the valve opening and closing for the discharge entirely independently of the movement of the piston, by means of suitable cams, whilst for 45 instance in the case of control exclusively by slots, one is positively tied to the movement of the air pump piston.

Practical experience demonstrates that the 50 maximum output of the hammer is dependent directly on the beginning and the duration of the discharge, relatively to the dead centre position of the piston, and as the most favorable moments of opening and 55 closing cannot be attained by means of slots, for kinetic reasons, a material improvement

is achieved by the use of the above mentioned controlled valve for the air discharge with simultaneous use of port belts in the cylinder for the air admission. 60

A construction according to the invention is illustrated in the accompanying drawing in which—

Figure 1 is a vertical central section through the air pulsator, and 65

Figure 2 is an outside elevation of the side situated on the left hand in Figure 2, the cover being removed.

The air pulsator illustrated is intended to produce alternate depression and compression in the hose pipe *b* leading to a pneumatic hammer. To achieve this result the shaft *c*, which is driven in a manner that need not be described, operates the piston *d* as for example by means of a crank connection with the piston. At the left hand outer end of the shaft *c* is arranged a valve rod *f* driven by a cam disc *e* and sliding in a guide *g*. At each revolution, the valve is opened and closed twice, once for the air discharge, and the second time, for supplementing the atmospheric air drawn in through the air slots, for the air admission. 70 75 80

As, however, for the air inlet slots the whole annular surface of the cylinder is available, as already stated, one cam which provides for the additional air admission may be suppressed. In any case it is immaterial for the substance of the invention. 85

From the foregoing description considered in connection with the accompanying drawings, the construction and the advantages of the invention will be readily understood. Although we have herein described some practical embodiments of our invention, which have given highly satisfactory results in actual use, it is nevertheless to be understood, that the essential features of our improvements might likewise be embodied in numerous other alternative constructions. Accordingly therefore, the privilege is reserved of resorting to all such legitimate changes in the form, construction and relative arrangement of the several parts as may be fairly considered within the 90 95 100 spirit and scope of the invention as claimed.

Having now particularly described and ascertained the nature of our said invention and in what manner the same is to be performed, we declare that what we claim is— 110

1. In an apparatus for producing pulsating air pressure, in combination, a cylinder,

a valve, a piston moving in the said cylinder, means for driving the said piston and the valve, the cylinder being provided with slots for admitting air to the cylinder by suction, the compressed air leaving the cylinder through the said valve.

2. In an apparatus for producing pulsating air pressure, in combination, a cylinder, a valve, a piston moving in the said cylinder, means for driving the said piston and the valve, the cylinder being provided with slots for admitting air thereto by suction,

the compressed air leaving the cylinder through the said valve, the valve being operated twice during each double stroke of the piston, in order to additionally admit air during the one stroke, and to exhaust the compressed air during the other stroke of the piston.

In testimony that they claim the foregoing as their invention, they have signed their names.

RICHARD KARL SCHMID.
WALTER PAUL WEZEL.
